(57) **CLAIM**

The ornamental design for an inductor, as shown and described.

DESCRIPTION

FIG. 1 is a front view of an inductor according to the claimed design, with the rear view being the same.

FIG. 2 is a top plan view of the inductor.

FIG. 3 is a bottom plan view of the inductor.

FIG. 4 is a right side view of the inductor.

FIG. 5 is a left side view of the inductor.

FIG. 6 is a first perspective view of the inductor; and,

FIG. 7 is a second perspective view of the inductor.

The broken lines in the drawings illustrate portions of the inductor that form no part of the claimed design.

The long-dash short-dash broken lines in the drawings define the bounds of the claimed design and form no part thereof.
